UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SNAP-SWITCH.

1,163,084.

Specification of Letters Patent.

Patented Dec. 7, 1915.

Application filed June 3, 1915. Serial No. 31,877.

To all whom it may concern:

Be it known that I, MONROE GUETT, a citizen of the United States, residing at Hartford, in the county of Hartford and State of Connecticut, have invented certain new and useful Improvements in Electric Snap-Switches, of which the following is a specification.

This invention relates to electric snap switches, among the principal objects of the invention being the provision of means of a simple and effective character for governing opposite movements of the switching member of whatever character the same may be.

15 As will be inferred, the switching member may be of any desired type; for instance the so-called "commutator" of a snap switch. This switching member or commutator may have one or more poles as may be required.

20 In the drawings accompanying and forming part of the present specification I have represented in detail one of the several convenient forms of embodiment of the invention which will be set forth in detail in the following description. I do not limit myself to this disclosure; I may depart therefrom in several respects within the scope of the invention defined by the claims following said description.

25 Referring to said drawings: Figure 1 is a top plan view of a switch involving the invention. Fig. 2 is a section on the line 2—2 of Fig. 1 looking in the direction of the arrow, the switching member being on. Fig. 3 is a similar view with the switching member off, the lower part of the body being removed. Fig. 4 is a section on the line 4—4 of Fig. 3, looking upward and showing the stop members or elements in their operative 30 positions, the cam means being in the neutral position. Fig. 5 is a similar view with the stop members and cam means in different positions as shown by full and dotted lines and as will hereinafter more particularly appear. Fig. 6 is a section on the line 6—6 of Fig. 2 looking in the direction of the arrow and showing by full lines the spring means tensioned and the parts just before the switching member is released, the dotted 35 lines showing the direction of movement of the outside sleeve and the condition of the spring means after a snap movement has been effected. Fig. 7 is a similar view with the spring means in the initial condition 40 thereof. Fig. 8 is a section on the line 4—4

of Fig. 3 looking downward illustrative of the detent plate and showing the operative portions of the stop members in different positions. Fig. 9 is a similar view showing by arrows the direction of movement of 45 said operative portions.

Like characters refer to like parts throughout the several figures.

As will be clear my switch comprises in its organization a suitable switching member mounted for back and forth movement. I prefer that this switching member be turnable about an axis by which I mean to imply that it may be rotary step-by-step in one direction or step-by-step in the other direction 50 or that it may be merely oscillatory. In the present case the switching member is rotary.

The different parts of the switch may be mounted in any convenient manner, for instance they may be supported upon an insulating base as 2 generally made of porcelain. The switching member shown consists of a commutator denoted in a general way by 3 having as represented two poles or connectors as 4 insulated as usual from each other and co-operative with contacts or terminals as 5 of "clip" type suitably connected with the insulating base or body. As will be understood the pole pieces or connectors 4 are superposed, and it follows as 55 a consequence that one pair of contacts 5 is in a higher plane than the other pair of contacts. Fastened by screws or otherwise to the body or base 2 is a suitable detent member, the ratchet plate 7 answering satisfactorily in this respect. As shown this detent or ratchet member 7 is fastened to the bottom of the cavity 8 in the upper side of said body 2 approximately centrally thereof. Extending through and turning in a practically central opening in the detent member or ratchet plate 7 is a spindle as 8, this spindle also turning in the bushing 9 and being held against accidental withdrawal in some suitable way as by the split 60 ring 10 connected with the lower end thereof. Rigid with and rising from the commutator is the tube 11 having as shown the circumferential slot 12 extending from practically its base to its top. This tube receives within it the tube 13 having a practically similar slot 14 extending from the head 15 to the bottom thereof. Tightly fitted around the head 15 is the collar 16, the head 15 overlying the upper surface of 65

the collar or ring 16. The tube 13 and collar 16 are therefore, rigid with each other. Connected with the upper end of the spindle 8 is the handle 17. The spindle 8 extends through the inner of the two concentric tubes and is driven through the head 15 of the inner tube. In addition the handle 17 is keyed to the head 15. Inclosed by the inner tube 13 and surrounding the intermediate portion of the turnable spindle 8 is the coiled spring 18, the terminal coils of which have outward extensions or projections 19 and 20, the projection 19 being above the projection 20. When the spindle 10 and associated parts are in the neutral or idle position at which time the switching member 3 may be either on or off, the coiled spring 18 is under minimum tension, the slots 12 and 14 being in approximate register as shown in Fig. 7 and the projections or outwardly extending terminals of the spring bearing against the side walls of the two slots as shown in Fig. 7. It will be assumed that the handle 17 is turned in the 15 direction of the arrow associated therewith in Fig. 1. As a result thereof the inner sleeve 13 will be moved in the direction of the arrow in Fig. 7, the sleeve as it turns carrying the projection or extension 19 therewith and thus tensioning or winding the spring 18, this action continuing until the projection 19 is almost alined with the projection 20. During the action in question the switching member 3 is held against 20 turning movement, and when the spring is under the desired tension or when the projection 19 is nearly alined with the projection 20, the switching member will be released, as will hereinafter more particularly appear, the tube 11 being also released so that the projection 20 bearing against said tube can move the same from the full line position to the dotted line position in Fig. 6 following the direction of the arrow 25 therein. This particular view also shows by dotted lines the position of the projection 20 when the spring has exercised its snap function. If prior to the operation in question the switching member or commutator be on, it will be moved to off or vice versa. If the spindle be turned in the direction opposite to the arrow in Fig. 1, the 30 procedure just outlined will be exactly reversed, the spring 18 being tensioned or wound by the action of the inner tube 13 upon the projection 20.

The foregoing is a comparatively concise description of mechanism with which my improvements may be advantageously associated. As will be inferred from what has already been noted such improvements can be employed with equal advantage in conjunction with other constructions and so far as the improvements themselves are concerned, they may vary in their character,

the invention not residing in any particular details.

The detent or ratchet plate 7 to which I have already briefly alluded presents part of the controlling means for the switching member 3. As represented this detent member or ratchet plate 7 has four equidistantly disposed teeth 21, 22, 23, and 24. This detent member or ratchet plate co-operates with stop means which as illustrated comprise two stop elements as 25 and 26 pivoted at or near their butts to the under side of the switching member or commutator adjacent to the periphery thereof, these two stop elements being movable toward and from each other. They are constantly yieldingly forced to vary each other in some suitable way as by the bowed spring 27, the free ends of the branches of which fit in notches in the outer shorter arms of the lever like stop members or elements 25. As represented the active or operative portions of the duplicate or companion stop elements 25 and 26 consist of depending studs 28 and 29 near the free ends thereof. These two stop elements 25 and 26 in the present case have a flatwise or sliding bearing and guiding engagement against the under flat surface of the body of the switching member 3. When in their initial or neutral positions their adjacent flat faces 30 and 31 diverge slightly outward as shown in Fig. 4.

There is provided for the two stop elements 25 and 26 a suitable actuator such as the cam element 32 which turns with the spindle 8, said actuator or cam as represented having keyways in its opposite sides to receive the keys 33 of the inner tube 13 which as will be remembered is rigid with said spindle 8. In the present case the cam centrally receives said spindle 8 and it has the diametrically opposite lobes or actuating portions 34 and 35 adapted on the turning of the spindle 8 to effect the operation of the stop elements 25 and 26. Normally or when the switching member or commutator is at a state of rest the two actuating portions or lobes 34 are disposed centrally between the flat surfaces 30 and 31 of the two stop elements 25 and 26. One stop element controls the movement of the switching member in one direction, while the other stop element serves a similar function with relation to the switching member in the opposite direction, and the construction is such as will hereinafter more particularly appear that the stop members are moved to releasing positions successively. For example it will be assumed that the spindle is being turned to the right. The stop element 26 on such motion of the spindle is first moved to releasing position after which the stop element 25 controlling the movement of the switching member to the right, is moved to releasing position, so

that the desired action of the switching member can be accomplished only when the particular stop member controlling the desired motion, is in freeing relation.

In Fig. 4 the actuator or cam member is shown as occupying its neutral position. At this time as will be obvious, the switching member 3 which carries the stop members 25 and 26 may be either off or on, and the operative portion of one of the stop elements will be in engagement with an arresting portion of the detent member 7, such arresting portion being one of the several teeth 21 to 24 inclusive. The stud or pin 28 of the stop element 25 is shown (Fig. 8) as being against one side of the tooth 24, while the stud or pin 29 of the stop element 26 is shown as being against the opposite side of the tooth 22, both studs as will be clear being in tooth spaces, the bottoms of which constitute the periphery of the body of the detent member or ratchet plate 7. It will be clear, therefore, that if the spindle 8 be turned in either direction, the switching member or commutator 3 will not be initially turned, for the tooth 24 will prevent movement in one direction of the commutator, while the tooth 22 will prevent opposite movement of said commutator until the spring 18 has been tensioned or wound the requisite extent at which time the pins or studs 28 and 29 will have been moved to freeing positions.

It will be assumed that it is desired to turn the spindle to the right or clockwise in the direction of the arrow in Fig. 1 to obtain a movement of the switching member or commutator in a corresponding direction as indicated by the arrow in Fig. 4. On the initial movement of the spindle 8 in the direction indicated the tensioning of the spring 18 will be inaugurated, the cam 32 being moved toward the dotted line position in Fig. 5. What is shown as the upper lobe 25 in Fig. 4 will strike the flat face 31 of the stop element 26 and riding along said flat surface will swing the cam element 26 outwardly to carry the pin or stud 29 out of the tooth space it occupies and outside of the boundary of the outer concentric faces of the teeth 21 to 24 inclusive. After what is shown in said Fig. 4 as the upper lobe of the cam 32 strikes the flat surface of the cam element 26 the lower lobe will strike the adjacent surface of the stop element 25, beyond which point or on the continuation of the predetermined movement of the spindle 8, the stop element 25 will be operated so as to swing the pin or stud 28 free of the tooth 24 and outside of said boundary line.

As is noted I move the stud 29 to its extreme outer position before the stud 28 reaches such position. During the turning of the spindle and the outward movement of the two studs 29 and 28 the spring 18 is

being tensioned, the maximum tension being reached just as the stud clears the tooth 24. At this point the commutator 3 will be wholly released so that the tensioned spring by relaxing can snap the said commutator 70 from the position it occupied which may be assumed to be on to off, the pin 28 being moved to the dotted position *a* in Fig. 8 and the pin 29 being moved to the dotted position *b*. In this second position if the 75 spindle be again turned toward the right, the stud 29 will be first moved to freeing position after which the stud or pin 28 will be moved to freeing position. It will be supposed that it is desired to turn the spindle to the left when the parts are in the initial position shown in Fig. 4, the spindle so turning on one predetermined movement thereof as to carry the cam 32 from the full line position shown in Fig. 4 to the full 80 line position in Fig. 5, and in this event the pin 28 will be first moved to releasing position after which the pin 29 will be moved to releasing position, for on such movement of the spindle the stop element 26 governs the 85 operation of the switching member or element 3. In this latter event the pin 28 would move from the full line position in Fig. 8 to the dotted line *c*, whereas the pin 29 would move from its full line position in said Fig. 8 to the position *d* in said view. In Fig. 9 I have indicated by arrows the direction of movements of the pins when the spindle 8 is turned in succession oppositely. While it is desirable and advantageous that the stop elements be moved successively to releasing positions, this may not be in all cases essential.

What I claim is:

1. A switch comprising a switching member, a stationary detent, stop members movably supported by the switching member and normally engaging the detent, spring means to apply its effect to the switching member, the switching member being oppositely movable, one stop member controlling the movement of the switching member in one direction and the other stop member controlling the movement of the switching member in the opposite direction, and means for tensioning the spring means to effect the predetermined movement of the switching member when the same is freed and for also moving to releasing position that stop member controlling the desired motion of the switching member.

2. A switch comprising a switching member, a stationary detent, stop members movably supported by the switching member and normally engaging the detent, spring means to apply its effect to the switching member, the switching member being oppositely movable, one stop member controlling the movement of the switching member in one direction and the other stop member con-

- trolling the movement of the switching member in the opposite direction, and means for tensioning the spring means to effect the predetermined movement of the switching member when the same is freed and for also moving to releasing position the two stop members, the stop member controlling the desired motion of the switching member being moved to releasing position after the 10 companion stop member is in releasing position.
3. A switch comprising a switching member, a stationary detent, stop members movably supported by the switching member 15 and normally engaging the detent, spring means to apply its effect to the switching member, the switching member being oppositely movable, one stop member controlling the movement of the switching member in 20 one direction and the other stop member controlling the movement of the switching member in the opposite direction, means for tensioning the spring means to effect a predetermined movement of the switching 25 member when the same is freed and for moving to releasing positions the two stop members, and means for returning the stop members automatically to operative positions.
- 30 4. A switch comprising a switching member, a stationary detent, stop members pivotally supported by the switching member and normally engaging the detent, spring means to apply its effect to the switching member, the switching member being oppositely movable, one stop member controlling the movement of the switching member in one direction and the other stop member controlling the movement of the switching 40 member in the opposite direction, means for tensioning the spring means to effect the predetermined movement of the switching member when the same is freed and for also moving to releasing position that stop member controlling the desired motion of the switching member, and spring means acting constantly to hold the stop members in operative positions.
5. A switch comprising a switching member, a spindle, spring means between the spindle and the switching member, a detent, and stop members on the switching member engaging the detent, the spindle being adapted when turned in either direction to 50 tension the spring means and having means when thus turned to move the stop members successively to releasing positions, the spring means when the stop members are in releasing positions acting against the switching member to impart a snap movement thereto.
6. A switch comprising a switching member turnable about an axis, a spindle extending through the switching member, a 55 stationary detent, spring means between the spindle and the switching member, and stop members pivotally supported by the switching member and normally engaging the detent, the spindle being adapted when turned in either direction to tension the spring means and having means when thus turned to move the stop members to releasing positions, the spring means when the stop members are in releasing positions acting against the switching member to impart a snap movement thereto.
7. A switch comprising a switching member, a spindle extending through the switching member, spring means between the spindle and the switching member, a stationary detent through which the spindle extends, and stop members engaging the detent and carried by the switching member, said stop members controlling respective opposite movements of the switching member, the spindle being adapted when turned in either direction to tension the spring means and having means when thus turned to move the stop members to releasing positions, the spring means when the stop members are in 60 releasing position acting against the switching member to impart a snap movement thereto.
8. A switch comprising a switching member, a stationary detent supported independently of the switching member, pivotally supported by the switching member and normally engaging the detent and controlling opposite movements of the switching member, spring means to act 65 against the switching member, and oppositely movable means for moving the stop members to releasing positions and at the same time tensioning the spring means to cause the snap movement of the switching member on either of the movements of the oppositely movable means.
9. A switch comprising a switching member, a stationary detent, stop members movably supported by the switching member 70 and normally engaging the detent, the switching member being oppositely movable, one stop member controlling the movement of the switching member in one direction and the other stop member controlling the movement of the switching member in the opposite direction, a spindle, spring means between the spindle and the switching member, the spindle being adapted when turned in either direction to tension the spring 75 means and having means when turned to effect the movement of the stop member controlling the predetermined movement of the switching member to releasing position, the spring means when tensioned on the release of the switching member being adapted to impart a snap movement to said switching member.
10. An electric switch comprising a stationary detent, the body of which is approxi- 80

mately circular and is provided with several teeth, a switching member located at one side of the detent and oppositely movable about an axis, a spindle extending through 5 the switching member and the detent, stop members pivotally mounted on the switching member and the operative portions of which engage teeth of the detent to prevent accidental movement of the switching member, a spring between the stop members to hold the same normally in active or restraining relation, one stop member controlling the movement of the switching member in one direction and the other stop member 10 controlling the movement of the switching member in the other direction, a spring interposed between and connected respectively with the spindle and with the switching member and adapted to be initially tensioned by the spindle when the same is turned in either direction, and a cam rigid with the spindle for moving the stop members to releasing positions after the initial tensioning of the spring, the stop member 15 which controls the particular movement of the switching member being last released.

11. An electric switch comprising a detent 20 having peripheral teeth, a switching member located at one side of the detent and oppositely movable about an axis, a spindle 30 extending through the switching member and the detent, stop members movably mounted on the switching member and the operative portions of which engage teeth of the detent to prevent accidental movement of the switching member, one stop member controlling the movement of the switching member in one direction and the other stop member controlling the movement of the switching member in the other 35 direction, a spring interposed between the spindle and the switching member and adapted to be initially tensioned by the spindle when the same is turned in either direction, and a cam rigid with the spindle 40 for moving the stop members to releasing positions after the initial tensioning of the spring.

In testimony whereof I affix my signature in presence of two witnesses.

MONROE GUETT.
